CLOSURE FOR CONTAINERS

Brewster Stickney, Philadelphia, Pa.

Application July 17, 1940, Serial No. 346,035

10 Claims. (Cl. 221—102)

This invention relates to closures for bottles, tubes, cans, and other containers in which liquid, semi-liquid, soft plastic or powdered dentifrices, skin lotions, soaps, polishes, sauces, and materials of similar characteristics are packed, and from which the contents are discharged from time to time in relatively small quantities.

One object of the present invention is to provide a closure for containers of the types noted above by which relatively small but adequate quantities of the contents of the container will be measured uniformly, to eliminate wastage, and which may be sold with and as a part of the original package, separately as an accessory to replace the ordinary closure of the container, or distributed as an advertising novelty.

Another object of the invention is to construct the device of a minimum number of simple parts adaptable to manufacture under mass production methods, by automatic machinery, to reduce the cost to a minimum.

Another object of the invention is to construct the dispensing closure device in such a manner that it will serve, for example, as a tooth brush holder when applied to a bottle containing liquid dentifrice; and in such a manner that the handle of the tooth brush may be utilized, when packed with the container inside an outer original package, or when being carried in a traveling bag, trunk, etc., as a retaining link between relatively movable parts of the device, to prevent accidental ejection of the contents of the container.

The construction and operation of various representative forms of the device will be fully disclosed hereinafter, reference being had to the accompanying drawings of which:

Fig. 1 is a sectional elevation of one form of container equipped with a dispensing cap constructed in accordance with the principles of the present invention;

Fig. 2 is a plan view of the cap shown in Fig. 1;

Fig. 3 is a side elevation, at right angles to Fig. 1;

Fig. 4 is a view similar to Fig. 1 showing the container and cap in dispensing position;

Figs. 5, 6, 7 and 8 illustrate modifications of the device.

In the device shown in Figs. 1 to 5, inclusive, the body 1 of the closure element is in the form of a nipple-shaped cap. However, the closure may be of any desired external shape and may be composed of any desired material. Preferably the cap 1 is composed of one of the various well known modern plastic materials, or hard rubber,

Bakelite, etc., which may be readily molded to the desired shape.

The body 1 of the cap is provided with an internal axial bore 2 which may be molded directly therein. The bore 2 terminates at the inner end of the cap 1 in an enlarged internally threaded cavity 3, which is adapted to receive the externally threaded neck 9 of a bottle, tube, can, or other form of container 5.

10. Preferably the base of the cavity 2 is provided with an annular groove 6 for reception of a sealing ring 7, which is adapted to be pressed into sealing contact with the end surface 8 of the neck 9 of the container 5.

15. The opposite outer end of the internal bore 2 is closed by a head 10 which is molded integral with the body 1. The head 10 is counter-bored for reception of a tubular piston rod 11 which extends longitudinally through and in axial alignment with the internal bore 2 and projects beyond the opposite ends respectively of the body 1.

Adjacent the outer end 10 of the body 1, the tubular piston rod 11 is provided with a collar 25, 12 to which is secured a U-shaped stirrup-like element 13 composed of resilient metal and including two correspondingly shaped side pieces 14, 14 arranged in parallel spaced relation to each other, with a space 15 therebetween. Each 30. of the side pieces 14, 14 is provided with an opening 16, for purposes hereinafter described.

The opposite or inner end of the tubular piston rod 11 is closed by a suitable internal plug 17 and is provided with an external collar 18. 35. Secured to the tubular rod 11, in axially spaced relation to the collar 18, is a second collar 19. Slidably mounted on the tubular piston rod 11, intermediate the collars 18 and 19, is a piston 20 which is adapted to fit snugly within and be movable longitudinally of the internal bore 2 of the cap body 1.

As shown in Fig. 1, the collar 19 is normally spaced below the inner or normally lower open end of the cylinder bore 2. The piston 20 normally rests, by gravity solely, against the upper surface of the collar 18. Immediately above the upper end of the piston 20 the tubular piston rod 11 is provided with a transverse passage 21.

When it is desired to eject a measured quantity of the contents x of the container 5, for example, onto the bristles 22 of a tooth brush 25, the container 5 is tilted to a suitable angle to cause the contents x of the container to flow around the outer surface of the piston 20, through the neck 9 of the container, and into the

cylindrical bore 2 in the body 1 of the closure. The head portion 25a of the brush 25 is then inserted through the aligned openings 16, 16 in the stirrup side plates 14, 14 respectively, as shown in full lines in Fig. 4. Outward movement of the stirrup 13, by pressure applied manually through the back of the head 25a of the brush 25 against the cross pieces 26 at the outer ends of the brush receiving openings 16, 16 in the side pieces 14, 14 respectively, will move the stirrup 13 from its normal full line position in Fig. 4 to its operative position shown by broken lines therein.

The above noted movement of the stirrup 13 will first cause the piston 20 to move into and seal the open end of the cylindrical bore 2, trapping a measured quantity of the contents x in said cylindrical bore between the one end of the piston 20 which normally faces the open end of the bore 2 and the head 10 closing the opposite end of said cylindrical bore.

Continued movement of the stirrup 13 will move the piston 20 correspondingly through the cylindrical bore 2 toward the closed end 10 thereof and cause the quantity of the contents x of the container 5 which has been trapped and isolated in the bore 2 to be forced into and through the transverse passage 21 of the tubular piston rod 11, into and through the longitudinal or axial passage 27 of said tubular piston rod and out of the open end 28 of the tubular piston rod 11, in the space 15 between the side plates 14, 14 of the stirrup 13 onto the bristles 22 of the brush 25, as illustrated in broken lines at x in Fig. 4.

The brush 25, with its measured quantity of the preparation x thereon, may then be used for its intended purpose and the container 5 returned to its normal upright position shown in Fig. 1.

The snug fit of the piston 20 in the cylindrical bore 2 will normally maintain the stirrup 13 in an extended position, with the collar 19 on the piston rod 11 resting against the normal upper surface of the piston 20. By forcing the stirrup 13 downwardly manually, the piston 20 is moved in the opposite direction within the cylindrical bore 2 and out the lower open end thereof, until the collar 12 rests on the head 10 of the cap 1. The piston 20 will then move by gravity along the rod 11 until it rests on the upper end of the collar 18, as shown in Fig. 1.

As noted above, the piston 20 is movable relative to the rod 11 between the collars 18 and 19 and in so doing it keeps the transverse passage 21 in the tubular piston rod 11 from becoming clogged by small accumulations of the preparation forming the contents x of the container 5, hardening or solidifying adjacent the passage 21.

Furthermore, the relative movement between the piston 20 and rod 11 will permit the piston 20 to slide on the rod and close the passage 21 against the escape of the contents x when the container is tilted, either accidentally or purposely, and will maintain the passage 21 closed until the stirrup 13 is moved in the manner previously described, whereupon the pressure of the material trapped in the bore 2 will force the piston 20 outwardly into contact with the collar 18 and expose the passage 21 for entrance of the trapped material into the longitudinal passage 27 of the rod 11, in ejecting the measured quantity of the contents from the container as previously described.

The space 15 between the side plates 14, 14 of

the stirrup 13 is preferably slightly less than the thickness of the handle 25b of the brush 25. The side pieces 14, 14 and the cross piece 28, which connects said side pieces and which is secured to the collar 12, are preferably punched from a single sheet of resilient metal. As a result of this construction the handle 25b of the brush 25 may be inserted between the side plates 14, 14 of the stirrup 13 which will then function as a spring clip to support the brush 25 firmly when not in use.

In order to prevent accidental dispensing of the contents x during shipping or when the container 5 is packed in one's luggage, the handle 25b of the brush is adapted to function as a link between the movable stirrup 13 and the body 1 of the closure, and for this purpose one end of the brush 25 may be swung downwardly into the broken line position shown in Fig. 1, wherein the one end of the handle 25b is resiliently gripped by and between the side plates 14, 14 of the stirrup 13 and a relatively spaced portion of the handle 25b is gripped by and between a pair of spring fingers 30, 30 which project laterally from the body portion 1, as clearly illustrated in Figs. 1 and 2.

For the sake of simplicity, the fingers 30, 30 constitute the ends of a continuous spring wire. This wire also includes an annular portion 31 which is adapted to be seated in a circumferential groove 32 formed in the body portion 1, as clearly illustrated in Figs. 1, 2 and 3.

For original shipping purposes the handle 25b of the brush 25 may be supplanted by any form of link element, for example, as by a strip of wood, cardboard, etc. which may bear printed instructions or advertising matter, or by a wire or cord.

If the device is to be used for dispensing liquid soap, for example, the stirrup element may be gripped in one hand in a manner to direct the liquid from the open end 28 of the tubular piston rod 11 into the palm of the hand, with the device tilted as shown in Fig. 4, and held in the other hand. The stirrup 13 may then be moved outwardly from the full line position to the broken line position, to squirt the measured quantity of liquid trapped in the cylindrical bore 2 into the palm of the hand which is gripping the stirrup 13. Obviously, under these circumstances, the stirrup, which broadly functions as the means for operating the piston, may take any desired form, for example, as a simple knob with a central bore forming a continuation of the central bore of the tubular rod 11, as shown in Fig. 6.

In the device shown in Fig. 5 the construction corresponding to that shown in Fig. 1, with the exception that the piston 20a is rigidly connected to the tubular piston rod 11a and the collar 18 and 19 are eliminated, the transverse passage 21a being disposed immediately adjacent the upper end of the piston 20a.

The device shown in Fig. 6 takes the form of a bottle stopper comprising a cork 35 adapted to fit snugly within the mouth 36 of a bottle 37 and provided with a disc 38 at one end adapted to rest against the end surface 39 of the bottle 37, the cork body 35 being secured to the disc 38, which may be of metal, wood, or of molded plastic material, in any well known manner, as by a waterproof adhesive.

The cork body 35 is provided with a metallic thimble 40 which forms a cylindrical bore 2b for reception and operation of a piston 20b which

is secured to one end of a tubular piston rod 11b, said tubular piston rod being provided with a transverse passage 21b similar to that described above.

The one end of the thimble 40 is open to receive the piston 20b and the opposite end of said thimble is closed by a head 10b which is bored for the passage of the tubular piston rod 11b. The outer end of the piston rod 11b is provided with a stirrup, knob, or other operating element 13b, as previously described. In operation, the device shown in Fig. 6 functions in substantially the same manner as described with respect to the device shown in Figs. 1 and 4.

Fig. 7 shows a still further modification where-in the stirrup 13c is composed of a single bent wire having its ends secured to a collar 12c on the tubular piston rod 11c, and providing an opening 16c large enough to accommodate a shoe brush or polish dauber.

In this case, the body 1c, with the bore 2c formed therein is held in the neck 9c of the container 5c by a crimped ring 45 or the like.

The piston 20c is secured to the inner end of the piston rod 11c and operates in the same manner as previously described when the device is tilted and the back of the applicator etc. is pressed against the cross bar of the stirrup 13c.

The structure shown in Fig. 8 is adapted primarily for sauces, catsup and other bottled dressings, etc. In this instance, the axial opening 40 in the neck 9d of the bottle or jar 5d serves as the cylindrical bore for reception and movement of the piston 20d, which may be rigidly secured to the tubular piston rod 11d, as in Figs. 5, 6 and 7, or which may be slidably mounted on said piston rod between collars 18d and 19d, as in Figs. 1 and 4. The tubular rod is also provided with a transverse passage 21d.

The piston rod 11d, in this case, projects through a metal cap 1d and sealing disc 1d. The sealing disc is centered with respect to the axial opening 40, and held tightly against the end surface 8d of the neck 9d by the cap 1d which may be of the ordinary crimped-edged type, with portions 41, 41 forced in and under a circumferential bead 42 formed on the end of the neck of the bottle.

The cap 1d and disc 1d close the upper or outer end of the axial cylindrical opening 40 in which the piston 20d is adapted to operate, the lower or inner end being open and convergent to receive the piston 20d where the neck 9d flares into the wider body portion 5d of the bottle.

The outer end of the tubular piston rod 11d is provided with an off-set stirrup 13d, which is adapted to receive a person's finger, for example, for actuating the piston rod 11d and consequently the piston 20d into, within, and out of the cylindrical bore 40. The stirrup 13d has a lug or collar 12d on one side thereof, in which the upper or outer end of the tubular piston 11d is secured.

If desired, the extreme outer end of the tubular piston rod 11d may terminate in a plane below that of the upper end of the collar 12d, and the upper end of the collar 12d may be dished or countersunk, as indicated at 43, concentric to the axis of the rod 11d, to cause any particles or drops of the contents of the bottle which may adhere to the end of the tubular rod 11d to run back into the tube rather than down the outside of the collar 12d onto the cap and bottle.

After an ejection from the outer end of the tubular piston rod has been effected, inward

movement thereof, and consequently of the piston in the cylindrical bore, creates a suction at the outer end of the rod, drawing any particles of the contents of the container, which may adhere to or remain near the discharge end of the tubular piston rod, back into the tubular piston rod, thereby keeping said discharge end clean.

Obviously, if packing around the piston rod is required, as may be when the device is used with contents of light viscosity, such for example as perfumes, etc. containing a high percentage of alcohol, such packing could be employed without departing from the spirit of the invention. In Fig. 8 the disc 1d, which preferably is composed of cork, although any other suitable material may be used, will function as a packing around the piston rod 11d by merely making the bore in the disc fit the outside of the rod 11d snugly.

Should the longitudinal bore of the tubular piston rod become clogged, as when the device is being used with a heavy viscous substance, or otherwise, it is within the scope of the invention to thread the piston 20a, for example (Fig. 5), or the collar 18 (Fig. 1), to the inner end of the tubular piston rod in either case, and to secure a solid rod or wire 44, having either a pointed or a blunt end 45, in the collar or piston, as shown in Fig. 5, to depend normally from the inner end of the piston rod into the container. The ram rod 44 may be used when the device is removed from the container by unscrewing the collar or piston from the tubular piston rod and passing the free end of the ram rod through the bore of the piston rod, using the piston or collar as a head for operating the ram rod.

If desired, the tip 27a (Fig. 5) of the tubular piston 11a may extend slightly above the curved edge 16b of the brush receiving opening 16a in the stirrup 13a to be cleansed of adhering drops of the contents of the container merely by rubbing the brush across said tip 27a.

As the various forms described above are representative it will be obvious that other modifications may be developed without departing from the spirit of the invention.

I claim:

1. A container closure provided with an axial bore closed at the outer end of the closure and open at the inner end thereof, a tubular piston rod closed at its inner end and extending axially through said bore and beyond the opposite ends thereof, a piston on the inner end of said rod for operation in said bore and normally disengaged therefrom in axially spaced relation to said open end thereof, a transverse passage in said tubular rod between the piston and the open end of said bore, and a manually operable element mounted on and carried solely by the outer end of said rod constituting the sole means for reciprocating said piston as and for the purpose described.

2. A container closure provided with an axial bore closed at the outer end of the closure and open at the inner end thereof, a tubular piston rod closed at its inner end and extending axially through said bore and beyond the opposite ends thereof, a pair of collars fixed to the inner end of the rod in spaced relation to each other, a piston slidably mounted on said rod intermediate said spaced collars for operation in said bore and normally disengaged therefrom in axially spaced relation to said open end thereof, a transverse passage in said tubular piston rod intermediate one of said collars and the adjacent end of said piston, and a manually operable element on the

outer end of said tubular rod for actuating said piston as described.

3. A container closure including a tubular axially reciprocable rod having its inner end closed and provided with a fluid-displacing piston, said rod being further provided with an open contents-discharging end projecting from said closure, and a stirrup secured to said projecting end with an opening to receive and hold an extraneous element in alignment with the open discharge end of said rod, said element being adapted to operate said rod by contact with one end of said opening to eject a portion of the contents of the container onto said element.

4. A container closure including a tubular axially reciprocable rod having its inner end closed and provided with a fluid-displacing piston, said rod being further provided with an open discharge end projecting from the said closure, and a stirrup secured to said end for effecting axial movement of said rod relative to said closure, said stirrup comprising a pair of parallel plates disposed at opposite sides respectively of said rod and provided with aligned transverse openings for receiving an extraneous element for actuating said rod and to maintain alignment of said element with the discharge end of said rod.

5. A container closure including a tubular axially reciprocable rod having its inner end closed and provided with a fluid-displacing piston, said rod being further provided with an open discharge end projecting axially from the outer end of said closure, and a stirrup secured to said end for effecting axial movement of said rod relative to said closure, said stirrup comprising a pair of resilient parallel laterally spaced plates disposed at opposite sides respectively of said rod and provided with aligned transverse openings for receiving an extraneous element for actuating said rod and to maintain alignment of said element with the discharge end of said rod, said spaced resilient plates being adapted to receive and hold said element therebetween when not employed in operating said rod or otherwise.

6. A container closure including a tubular axially reciprocable rod having its inner end closed and provided with a fluid-displacing piston, said rod being further provided with an open discharge end projecting axially from the outer end of said closure, a stirrup secured to said end for effecting axial movement of said rod relative to said closure, said stirrup comprising a pair of resilient parallel laterally spaced plates disposed at opposite sides respectively of said rod and provided with aligned transverse openings for receiving an extraneous element for actuating said rod and to maintain alignment of said element with the discharge end of said rod, and a pair of resilient fingers projecting laterally from said closure below said stirrup, said resilient plates and said resilient fingers being aligned and adapted to grip relatively spaced parts of a link therebetween to prevent accidental reciprocation of said tubular rod.

7. A container closure, a tubular axially reciprocable rod having its inner end closed and provided with a fluid-displacing piston, said rod being further provided with an open discharge end projecting axially from the outer end of said closure, a stirrup secured to said end for effecting axial movement of said rod relative to said closure, said stirrup comprising a pair of resil-

ient parallel laterally spaced plates disposed at opposite sides respectively of said rod and provided with aligned transverse openings for receiving an extraneous element for actuating said rod and to maintain alignment of said element with the discharge end of said rod, and a pair of resilient fingers projecting laterally from said closure below said stirrup, said resilient plates and said resilient fingers being aligned and adapted to grip relatively spaced parts of a link therebetween to prevent accidental reciprocation of said tubular rod, said fingers constituting the ends of a continuous spring wire including an annular portion seated in a circumferential groove formed in said closure.

8. A container closure provided with an axial bore closed at the outer end of the closure and open at the inner end thereof, a tubular piston rod closed at its inner end and extending axially through said bore and beyond the opposite ends thereof, a piston on the inner end of said rod for operation in said bore and normally disengaged therefrom in axially spaced relation to said open end thereof, a transverse passage in said tubular rod between the piston and the open end of said bore, and a manually operable element including a hub portion having one of its ends secured on the outer end of said rod with said outer end of said tubular rod terminating at a plane between the opposite ends of said hub in a recess countersunk below the outer surface of the opposite end of said hub, said element constituting the sole means for reciprocating said piston as and for the purpose described.

9. A container closure provided with an axial bore closed at the outer end of the closure and open at the inner end thereof, a tubular piston rod extending axially through said bore and beyond the opposite ends thereof, a piston on the inner end of said rod for operation in said bore and normally disengaged therefrom in axially spaced relation to said open end thereof, said piston having an internally threaded passage in axial alignment with and forming a continuation of the axial opening of said tubular piston rod, a transverse passage in said tubular rod between the piston and the open end of said bore, a manually operable element on the outer end of said rod constituting the sole means for reciprocating said piston, and an element having a threaded end screwed into said threaded passage in said piston and forming a closure plug for the inner end of said tubular piston rod with the opposite end of said plug normally depending therefrom into the container, as and for the purpose described.

10. A container closure including a tubular axially reciprocable rod having its inner end closed and provided with a fluid-displacing piston, said rod being further provided with an open contents-discharging end projecting from said closure, and a stirrup secured to said projecting end with an opening to receive and hold an extraneous element in alignment with the open discharge end of said rod, said stirrup including a cross bar for engagement by said element to operate said rod to eject a portion of the contents of the container onto said element, said open end of said tubular rod projecting beyond the edge of said element receiving opening in said stirrup, as and for the purpose described.

BREWSTER STICKNEY.
